(57) **CLAIM**

The ornamental design for a rear kick-up for a snow vehicle, as shown and described.

DESCRIPTION

FIG. 1 is a top and right side isometric view of a rear kick-up for a snow vehicle embodying our new design;

FIG. 2 is a front perspective view with the rear end elevated above the front end thereof;

FIG. 3 is a rear perspective view with the rear end elevated above the front end thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a top and left side isometric view thereof.

The broken lines in the drawings depict portions of the rear kick-up for a snow vehicle that form no part of the claimed design.
